ATTORNEYS.

UNITED STATES PATENT OFFICE.

AMOS F. B. HARRADEN, OF MOUNT VERNON, NEW YORK.

DESIGN FOR A LIGHTING-FIXTURE.

56,154.

Specification for Design.

Patented Aug. 24, 1920.

Application filed April 17, 1919. Serial No. 290,868. Term of patent 7 years.

To all whom it may concern:

Be it known that I, AMOS F. B. HARRADEN, a citizen of the United States, and a resident of Mount Vernon, in the county of Westchester and State of New York, have invented a new, original, and ornamental Design for a Lighting-Fixture, of which the following is a specification, reference being

had to the accompanying drawing, forming part thereof.

The figure is an isometric perspective view of the fixture.

I claim:

The ornamental design for a lighting fixture, as shown.

AMOS F. B. HARRADEN.
